CLAIM

The ornamental design for an attachment for chiropractic device, as shown and described.

DESCRIPTION

FIG. 1 is a front view of an attachment for chiropractic device showing our new design;

FIG. 2 is a left side view thereof;

FIG. 3 is a top view thereof;

FIG. 4 is a bottom view thereof;

FIG. 5 is a top perspective view thereof; and,

FIG. 6 is a bottom perspective view thereof.

A rear view is omitted since the rear view is identical to the front view. A right side view is omitted since the right side view is identical to the left side view.

1 Claim, 6 Drawing Sheets
